UNITED STATES PATENT OFFICE.

SILVANUS F. VAN CHOATE, OF NEW YORK, N. Y.

ELECTRIC-ARC LAMP.

SPECIFICATION forming part of Letters Patent No. 309,012, dated December 9, 1884.

Application filed June 24, 1881. (No model.)

To all whom it may concern:

Be it known that I, S. F. VAN CHOATE, a citizen of the United States, residing at New York, in the county of New York, and State of New York, have invented certain new and useful Improvements in Electric Lamps, of which the following is a specification.

My invention relates to that class of electric lamps known as "arc lamps," in which the conducting sticks or pencils are placed end to end, and fed toward one another as they consume.

My invention consists in certain novel devices for feeding both carbons toward one another and for determining the length of arc.

My invention consists, further, in certain novel devices for supporting the various parts of the lamp, and for securing a reflecting-hood to the globe surrounding the light, whereby the lamp described in my Patent No. 268,155 is adapted for use with electric-arc lights in which the carbons are placed end to end.

My invention finally consists in certain details of construction, which will be specified in the claims.

The features of construction relating to the reflector and the devices for making connection to the lamp are also applicable to incandescent electric lamps, as will readily appear from the annexed description.

In the accompanying drawings, Figure 1 is an elevation of the lamp. Fig. 2 is a vertical section of the lower part of the lamp, showing the details of construction relating to the regulating and feeding mechanism and the devices for supporting the same and conveying the current to the light. Fig. 3 is a detail section of the upper part of the lamp, showing the construction of the hood and reflector and the means employed for securing the various parts together. Fig. 4 is a detail view illustrating the path of the current through the lamp, and showing, also, a modified arrangement of the electro-magnetic devices for controlling the carbons. Fig. 5 is a bottom view of the casing and supporting devices. Fig. 6 is a top view showing the devices for holding and clamping the lower carbon. Fig. 7 is a vertical section of devices to be employed for making electrical connection between the lamp and the main conductors. Fig. 8 is a

section of the lower part of a supporting post or bracket, showing devices that may be employed for cutting off the current when the lamp is lowered in its support or bracket for repair or removal or for the insertion of new carbons. Fig. 9 is a detail view of the spring-clamp.

Referring to Fig. 2 of the drawings, P represents a hollow supporting-post, upon the top of which an inclosing globe for the light is supported in the manner set forth in my patent above referred to, or in any other suitable manner.

B is a tube of metal fixed in the upper part of the post and acting as a support and guide for the cylindrical movable case A, of metal, containing the mechanism of the lamp proper.

C is a stirrup or bracket secured to the lower part of the case by means of screws or bolts, a, while D represents the top of a supporting rod or tang depending within the post to a point where it may be reached from a door or opening in the post below. This rod is secured in a cross-piece, b, by means of a nut, e, as shown, and serves to hold the lamp proper in an elevated position or to lower the same to the level of the door or opening in the manner described in my application above named.

F is a hollow cylinder, of wood or other insulating material, fitting closely within and secured to the metallic tube A. This cylinder serves as a means of attachment and support for the various mechanisms, and also as an insulation between the various parts. Within this cylinder are fixed in any suitable manner two spools, F F², the lower one of wood or bone, rubber, or other non-magnetic material, such as brass, and the upper of soft iron, 9c which hold two coils or helices of insulated wire, the upper coil in the circuit with the carbons and acting as the regulating-coil, and the lower in a derived circuit around the carbons. These spools are bored centrally for the passage of the lower carbon and holder. A hollow cylinder, of brass or other metal, is fastened within the lower spool, and is screwed into the lower end of the iron spool, so as to hold the two spools in line and firmly together. It serves also as a guide for the hollow metallic tube within which the lower car-

bon is supported, and through which it is fed upward by the devices to be presently described.

G is a circular armature of iron encircling 5 the tube of copper or other non-magnetic metal and fastened thereto. It is arranged to be attracted by the upper metallic spool of iron, to whose upper face is secured a piece of felt or other material which serves to prevent the 10 armature from sticking and to deaden the sound or click of the armature when it is brought forcibly down in contact with the head of the spool. The edge of the armature is slightly beveled, for the purpose of imparting 15 movement to devices bearing against the armature at that point, which serve to release and to hold the upper carbon. The range of upward movement of the armature is controlled by an adjustable screw tap or sleeve, 20 H, which incloses the tube f, and is provided upon its exterior with a screw-thread for engagement with a screw-thread upon the interior of a boss or sleeve projecting downward from a cap-plate, g. The sleeve is provided 25 with a milled head, whereby it may be adjusted vertically. The hollow tube f, which carries the lower carbon, and to which the armature G is attached, is supported by a coiled spring, k, the upper end of which rests against 30 a collar, m, secured to the tube f, while its lower end rests upon adjusting and set nuts j, j, by means of which the degree of compression of the spring may be regulated. These nuts are adjustable upon an upright hollow 35 tube, i, which is provided with a screw-thread upon its exterior, and is secured at its lower end to a plate on cross-bar h, (shown in bottom view, Fig. 5,) fastened by screws to the lower end of the insulation-cylinder E. 40 Electrical connection with the tube f and the lower carbon for the outgoing current is made by means of a metal block, l, fastened to the lower end of the tube and provided on either side with binding-posts p, p for wires 45 leading from the lower spool, and to the outside conductors. (See Figs. 4 and 5.) The lower carbon, K, is held within the tube f by means of a spring, x, (seen in Figs. 6 and 9,) secured to the tube at its upper end, 50 which spring is slightly rounded at its bearing end, so as to allow the tube to move up and down whenever the carbon is clamped by devices to be hereinafter described, but which bears against the carbon with sufficient force 55 to cause the tube and carbon to move together under other conditions. The upper carbon, L, is supported and guided in a tube or holder, J, firmly secured to metallic rod I, bent at its upper extremity and entering a socket or boss 60 in the side of the tube. The rod I is supported in the insulating-cylinder E, and is in electrical connection with one end of the helix upon the upper spool of metal. This connection is illustrated diagrammatically in Fig. 4. 65 The rod I, as well as the rod M, which serves also in a measure to support the tube, as will

be seen, passes upward within the globe instead of upon the outside thereof, as in electric lamps of the ordinary form, in which the carbons are placed end to end. This not only simplifies 70 the construction, but also gives a more pleasing appearance to the lamp, and when the globe is opalescent or of ground glass does away with the black and well defined shadows which occur where the supports for one of the 75 carbons are placed outside of the globe. The improved result in the latter particular is probably due to the diffusion of the light by the material of the globe itself, and the reflections from one point of the interior surface 80 thereof to another.

The clamp and detent which controls the movement of the upper carbon consists of a rod, M, similar to I, which is provided at its end with a chisel-point, w, forming a clutch 85 or detent, and adapted to engage with the surface of the carbon and hold it from sliding downward. The end w plays freely in the boss or opening in the side of the tube. The rod M is supported in an upright lever, N, of 90 bone, rubber, or other insulating material, which is pivoted in a slot in the insulation-cylinder E at the point r, the bracket s upon which the lever is pivoted being secured to the cylinder E in the manner shown. A spring, 95 t, fastened to cylinder A, bears against the lever and tends to hold the chisel-point w against the upper carbon, while an adjustable screw-spring, u, passing through the lever, and adapted to bear with its rounded or beveled point 100 against the beveled edge of the armature, serves to withdraw the clutch w when the armature is raised by the action of the supporting-spring k. A screw-stop, v, passing through the cylinder A, limits the backward play of the lever. 105 When the chisel point or end of rod M presses against the carbon-rod L, the latter will be firmly held suspended in and against the sides of the hollow tube or socket J, notwithstanding the lower carbon, K, may be lowered or 110 entirely removed; but when the lower carbon is separated from the upper, on moving rod M to the right the slightest degree, the carbon L would instantly fall by gravity until the lower end was arrested by the lower carbon, or until 115 the rod M again pressed its point W against the side of the carbon. The contact and pressure against the carbon and the removal of said pressure and contact is brought about by the armature G on the one hand and by the 120 spring t on the other. The dummy spool F², of wood, bone, or rubber, and the soft-iron spool F, as I have already remarked, are wound with a few layers of conducting-wire, the wire on the iron spool being, preferably, a little 125 coarser than that on the lower or dummy spool, so that the resistance in the two, including the carbons and the various connections, may be nearly equal. The circuit around the iron spool should be of a little less resistance than 130 the circuit through the wire on the dummy spool. The connections of the spools or heli-

ces, the carbons, and the other devices are shown in Fig. 4. The current entering at main wire 1 on arriving at 2 branches. The left-hand wire passes around the iron spool 5 and to arm or rod I, carbons L and K, tube f, collar l, wire 3, and on to the next lamp or to earth, as the case may be. The right-hand wire or circuit passes around the wooden spool and out through wire 4 to collar l, where it joins 10 the main line again. As will be seen, the circuit is divided between the two spools and formed into multiple arc, while one branch does not pass through the carbons or are and is never broken, but simply acts as a continu- 15 ously-closed circuit, to keep the current in the main or general circuit closed and steady during the imperfect contacts or variations of the current on passing through the carbons and the lamp mechanisms. The dummy spool and 20 its bobbin may, if desired, be located in other positions. The position shown is chosen for the sake of convenience and simplicity in construction.

The action of the iron-spool magnet, the 25 armature G, and the stop-pin u and rod M with its chisel-point w, is as follows: In the normal state of the lamp, and when no current is acting on the iron core of the magnet, the spiral spring k raises the tube f, armature 30 G, and carbon K until the armature comes against the hollow adjusting-nut H. In its upward movement the beveled edge of the armature acts upon adjustable pin u, thus withdrawing chisel-point w of rod M from contact- 35 pressure against carbon L, when the latter drops down upon the point of carbon K. This is the position of the various parts named when the electric current is turned through the circuit. The instant this is done the two 40 carbons begin to burn at their contact-points, but the arc does not and cannot form until the two points of the carbons in contact are slightly separated. This separation is also instantly brought about by the current caus- 45 ing the soft-iron spool to attract the armature G, which pulls down the tube f and carbon K. This movement—that is, the downward move- 50 ment of the armature G—brings its beveled edge away from the screw-point u and allows the chisel-edge of arm M to engage and hold fast the upper carbon and prevent it from following the downward movement of the lower carbon. The pin u may be so adjusted that this result will be produced on the slight- 55 est movement of the armature G. The separation of the two points of the carbons a cer- 60 tain distance forms an arc of a certain kind and gives a certain tension or strength in the current. The spring k is adjusted to this cer- 65 tain tension or current strength, and so regulates the armature G—that is to say, this cer- tain tension or strength of current holds down the armature against the set strength of the spiral spring k, but if the current strength

be increased, the spring k lifts or raises the tube f and armature G, and thus pressing back the arm or rod M allows or causes the upper carbon to begin to drop and so meet or 70 approach the ascending or rising carbon, when the arc or space between the carbon-points is decreased and the current is consequently increased, and so causes the armature and lower carbon to descend, and again the arc is reg- 75 ulated to the set or required strength of the current. This operation is repeated as often and as regularly as the variation in the distance between the points of the carbons takes place.

80

I have shown how the upper carbon, L, is regulated, and how the lower carbon and its carrying-tube f is raised and lowered together; but now I will explain how the lower carbon, K, is moved within the tube, and also describe 85 the devices employed for positively locking the lower carbon at a determinate point in its downward movement with the armature, so as to prevent the formation of an arc of abnormal length and at the same time to allow the ar- 90 mature to continue its downward movement without the carbon. The top of the tube has cut upon its outside surface a fine screw-thread, upon which nut n may be made to move up and down by turning it between the thumb 95 and finger by its outer milled surface. The upper edge of this nut is beveled.

On each side of the tube f and nut n are two upright spring hooks or clutches o o, mounted upon the top plate, g, of case A A. On the 100 inner sides of these clutch-hooks are two beveled surfaces, so arranged as to be acted upon by the beveled end of nut n when the latter is raised by the tube f. The two spring hooks or clutches o o are so arranged as to press 105 firmly against the opposite sides of the carbon K, and by their beveled or chiseled edges or points hold the carbon firmly and prevent it from moving downward; but it will be seen that owing to the peculiar bevel of their points 110 the carbon could be moved upward notwithstanding the pressure of the hooks against its sides.

It is obvious that the end of the tube might 115 serve the function of the nut if it were bevelled at its end; but as it is difficult to make said tube of precisely the proper length, I employ the adjustable nut, which serves the practical purpose of adjustably shortening and lengthening the tube. The nut n can be so 120 set that on the upward movement of the tube f the bevel of the nut and that on the two hooks causes the latter to spread out and release their contact with the carbon; but on the tube f and nut n being moved downward the hooks 125 are again brought into contact with the carbon, thus holding it firmly.

At the top of tube f is located, as before explained, a flat spring, x, with a rounded or bent end firmly fixed to and in a slot formed 130 at the top of tube f and pressing firmly with its rounded end against the carbon K, thus

holding the latter firmly in the tube. The carbon can, however, be moved up and down notwithstanding the pressure of the spring.

Fig. 6 is a plan of the spring-hooks, &c., looking downward upon the top of case A A. The two rods M and I and the carbon K are shown in section. The two spring-clutches on hooks are shown at o o, while f indicates the tube carrying the carbon, and x the upper end of the spring which presses against and holds the carbon in the tube. The adjusting screw-pin n, Fig. 2, is set so that on lowering the armature G the chiseled point w of the rod M is brought against the carbon L, so as to hold the latter firmly before the two spring-clutches o o come into contact with the lower carbon, so that the descent of the upper carbon is arrested before the lower one begins to be separated from it. The beveled nut is so adjusted that the spring hooks or clamps o o do not clamp the carbon after the upper carbon ceases its downward movement until the space between the two points of the carbons is sufficient for the proper development of the voltaic arc, when the balance of the downward movement of the armature causes the spring x to slide on the side of the carbon and take a lower position along the side thereof. When the tube f and spring x are raised again by the action of the spring k, the carbon, being free to move in an upward direction between the clutches o o, is lifted. By this differential motion between the tube f and the carbon K the upper end of the latter is raised as it is consumed by the voltaic arc. This movement is repeated whenever the armature is carried below the point where the nut n releases the clutches and allows them to engage with the carbon so as to stop it in its downward movement.

Other forms of clutch may be substituted for that shown, and other devices moving with the armature and carbon-carrier may be employed for causing the clutches to engage and disengage the carbon.

A modification of my invention, in which an armature is made to take the place of the spring k and its adjuncts for raising the carbon and tube f, is shown in Fig. 4. In this case the lower spool is made of soft iron, like the upper spool, and an armature, G', similar to G, is firmly fixed to the tube f at a proper point below the spool. When the arc becomes abnormal, the lower spool becomes supercharged and raises the armature G' and the tube f in the same way as the spring k. The lower spool, F', is separated from the upper spool by a plate of non-magnetic material, 21, or, if desired, the two spools may be separated to a sufficient distance to prevent the one from affecting the other. It will be seen that this construction consists simply of two spools arranged end to end, and abutting against each other, or approximately so, and having a hollow tube or a rod passing axially through them, upon each end of which is secured an armature, the said armature being

operated conversely by the main current passing over the main line. This feature of my invention is not limited to a carrier of any particular construction, but may be employed with carriers of other forms besides that shown.

In order to do away with flexible conducting-wires passing down within the post from the mechanism of the vertically-moving casing and allow the casing to be raised and lowered more conveniently, I have adopted the arrangement shown in Fig. 7, which is a vertical section of the cast-iron post P, the casing A, and insulating-tube E, carrying the lamp proper.

Two strips of copper are represented by 23, while 24 indicates insulation between said copper strips and the cast-iron post. These strips of copper and their insulation are held by screws 25, passing through insulating-plugs 26, which may be held in place by applying cement at the blank spaces indicated at 27. The copper strips are connected to the two wire terminals of the main circuit. Two stout flat metallic springs, 28, secured at their upper ends by bolts 29, passing through the tube of insulating material E, connect with wires 1 and 3 by the aid of screw-nuts 30. When the case is raised up to its proper seat, the springs 28 press upon the flat surface of the copper strips 23, and, making good contact, keep the circuit closed. The wires 1 and 3 pass up through the coils and lamp, and so complete the circuit in that direction after the manner indicated in Fig. 4. The plates 23 may be continued down within the post to connect with underground wires, or they may be connected with aerial conductors brought to the top of the post. In the latter case they need only be long enough to make metallic contact for the springs 28 when the lamp is elevated.

Fig. 8 is a sectional view of a portion of the cast-iron post opposite the door in the side of said post where the attendant brings down the lamp for adjustment and renewal of the carbons or other burners.

Continuations of the two copper strips mentioned and shown in Fig. 7 are indicated at 23. A flat plate of brass, 31, forming a switch-lever fulcrumed or pivoted at 32 and carrying a knob, handle, or thumb-piece of insulating material, 34, by which the lever or switch is operated, is for the purpose of cutting off or shunting the circuit from the lamp above while the attendant is adjusting it or removing the carbons. Upon opening the door in the post the switch is turned across the copper strips, so that the current will take the direction of the arrows. The lamp can then be lowered and adjusted, &c., and raised again without the least danger from the electric current. When the lamp is replaced in its proper position, the switch-lever is turned downward and parallel with the copper strips, when the electric current can then flow through the lamp.

In my previous patent No. 268,155 the re-

5 reflector and hood on the top of the glass globe was partly fastened by a rod terminating in its lower end in a flat head, and at its top in a screw-thread and nut to bind and hold the hood and reflector firmly to the top of the globe; but in my present invention the lower part of the rod terminates in a hollow tube, 7, Figs. 2 and 3, trumpet-shaped or flanged out at its lower end, as shown in the drawings, the 10 projection or flange of the tube extending underneath the edge of the hollow in the glass or other globe, as at 8, while the space 9 between the projecting rim of the globe and the tube, as well as that shown at 13, is filled in 15 with cement or other binding material. The tube and hood or reflector of the lamp are also further supported and strengthened by a plate of metal or other material, marked 45, which is firmly secured to the sides of the tube and 20 reflector or hood by soldering or otherwise, as shown at 41 and 42. The upper end of tube 25 7 terminates with a rod and screw-nut, 6, the connection of the rod and tube at 14 being made by soldering or in any desirable manner. The joint and connection of the apex of the hood and the tube at 15 is also soldered or otherwise fastened. The tube 7 furnishes a 30 space for the upper carbon to extend upward above the top of the globe, and the funnel-shaped mouth guides the end of the carbon on raising the case so that should the end of the carbon not be in exact line of the hollow of the tube it would be directed and guided to a central position.

35 5 The rod and screw-nut may be dispensed with, and the ornamental finish or top of the hood could be soldered at 17; but the rod and screw-nut strengthen the parts and prevent extension from corrosion or loosening of the 40 soldering of the joints of the hood between its upper and lower apexes.

What I claim as my invention is—

1. The combination, with a hollow carbon-carrier, of a clamp attached thereto for supporting the carbon and adapted to slide upon the carbon when the latter is locked against movement, a clutch or detent for the carbon adapted to hold it stationary, and devices supported by the carbon-carrier which act upon 45 said clutch and cause it to engage with and disengage the carbon as the carrier is moved, substantially as and for the purpose described.

2. The combination, with a hollow carbon-carrier or support, a clamping or supporting device attached to and moving with said carrier and adapted to bear against the carbon and to hold or propel or to move upon the carbon when the same is locked against movement, a locking-clutch fixed upon a stationary support and arranged to normally rest 50 against the carbon and lock it against movement with its carrier, and a disengaging device attached to the carrier and acting upon the clutch to disengage it from the carbon, substantially as described.

65 3. The combination, with a hollow carbon

carrier or support, of a spring or friction clamp attached to said carrier and bearing against the carbon for holding it in its tube, a locking-clamp bearing also against the carbon and 70 adapted to lock it from movement in one direction only, and means attached to the carrier and acting upon the locking-clutch to disengage it from the carbon.

4. The combination of a hollow carbon-carrier, a spring-clamp carried thereby and bearing against the carbon or carbon-rod, a spring-locking clutch adapted to prevent movement of the carbon in one direction and to allow free movement in the other, and devices attached to the carbon-carrier arranged to release said clutch so that it may engage with the carbon and adjustable upon their support so as to determine the point at which in the movement of the carrier the carbon will 85 be locked against further movement.

5. The combination of a hollow carbon-carrier and a spring-locking clutch attached to a stationary support and adapted to engage with the carbon, and an adjustable block or lug upon 90 the carrier which impinges against the clutch as the carbon is moved up and down and removes the clutch from its locking position or allows it to lock the carbon, substantially as described.

95 6. The combination of a hollow carbon-carrier, an electro-magnet for moving the same, a spring locking-clutch attached to a stationary support and adapted to engage with the carbon and hold it from movement with 100 its carrier in one direction, but to permit free movement in the other, and an adjustable nut upon the carrier that is brought into and out of contact with the clutch as the carrier moves up and down and thereby throws the clutch 105 out of engagement with the carbon or allows it to engage therewith.

7. The combination, with the hollow carbon-carrier, of the adjustable nut encircling the carrier, and beveled upon its edge, which 110 edge engages with the clutch and serves as a means of shortening and lengthening said carrier.

8. The combination of the hollow carbon-carrier *f*, provided with its clamping-spring *x*, the upright clutches *o o*, beveled at their sides, and the adjustable nut *n*, beveled at one 115 edge.

9. The combination of the hollow carbon-carrier, the armature *G*, secured thereto, the 120 clamping-spring *x*, clutches *o o*, and adjustable nut *n*, substantially as described.

10. The combination of hollow carbon-carrier *f*, armature *G*, attached thereto, and adjustable hollow set-screw *H*, substantially as 125 described.

11. The combination of the upper carbon in an electric lamp, a detent or clutch supported by a lever, and an armature beveled at its edge and attached to the carrier of the lower carbon, substantially as described.

130 12. In combination with the lower-carbon

carrier of an electric lamp, a spring or sliding clamp connected to the carbon-carrier, a clutch adapted to engage with the carbon and prevent its movement in one direction, but to allow free movement in the other, means attached to the carrier for removing said clutch from engagement with the lower carbon, an armature attached to said carrier acted upon by a governing electro-magnet, a detent for the upper carbon, and intermediate operating devices between the detent and the armature of the lower-carbon carrier, substantially as described.

13. The combination of the hollow carrier for the lower carbon, the armature attached directly thereto and beveled at its edge, the upright pivoted lever and detent for the upper carbon, and the adjustable bearing-pin passing through the lever and adapted to engage with the beveled edge of the armature.

14. The combination, substantially as described, of a hollow carbon-carrier of non-magnetic material, an armature attached directly thereto, and a spool of iron wound with a regulating coil or helix of insulated wire, and provided with a central bore or passage for supporting and guiding the carrier.

15. In an electric lamp, the vertically-movable easing supporting the working parts of the lamp and carrying a hollow or tubular holder of insulating material, within which is fitted the lamp-magnet, consisting of the spool of iron wound with insulated-wire, as and for the purpose described.

16. The combination, substantially as described, of a tubular holder, E E, and the vertically-arranged spools F F², having one or more enlarged or flanged heads of iron wound with coils of insulated wire in the main or principal circuit with the light and in a derived circuit thereto.

17. The combination, substantially as described, of the tubular carrier E, a centrally-bored spool having an enlarged or flanged head of iron, a carbon or carbon-carrier passing through said spool, and an armature attached to the carbon-carrier and arranged within the magnetic field of the iron-spool head.

18. The combination, with a carbon carrier or support of non-magnetic material, of two centrally-bored spools arranged in line, having enlarged or flanged heads and wound with coils of wire in the direct circuit with the light and in a derived circuit thereto, and an armature-plate attached to said carrier and arranged within the magnetic field of one of the spool-heads, substantially as described.

19. The combination of casing E, spools F F², carbon-carrier f, and cross-piece h, supporting the spring upon which the carrier rests.

20. The combination of casing E, hollow spools F F², carrier f, cross-piece h, screw-threaded tube i, adjusting-nuts J, and spiral spring k, substantially as described.

21. The combination of the insulating-casing E, spools F F², provided with a central passage for the carbon-carrier, armature G, attached to said carrier, vertically-pivoted lever N, mounted within a slot in the cylinder E, and devices carried by said lever for controlling the movement of the upper carbon.

22. The combination, with the interior conductors leading to the lamp, of the means for exterior connections substantially as described, consisting of the insulating-plugs 26 and screws 25, passing through openings in the wall of the post.

23. The combination, substantially as described, of the vertically-movable lamp, the hollow post, the insulated conducting-strips, and the shunting-switch 31, located as described.

24. The combination, with the vertically-movable lamp, the inclosing-post, conducting-plates or metallic contacts attached to the interior of the post and connected to the outside circuit, and conducting-springs attached to the lamp and adapted to bear upon the conducting-plates when the lamp is elevated to a position for use.

SILVANUS F. VAN CHOATE.
